UNITED STATES PATENT OFFICE

EDWARD BOARD, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA

RIM RIVETING MACHINE

Application filed June 3, 1935. Serial No. 34,742.

My invention consists of a wheel riveting machine especially adapted to rivet the rims of disc wheels now commonly used in the automotive industry to the body discs by means of which the rims are supported from the hub. Its outstanding characteristic is perhaps its complete automatic operation. Ordinary riveting machines have heretofore been used for this purpose, but so far as I am aware, I am the first to invent an entirely automatic machine for this work. In the invention of the machine, I also invented an entirely new method of doing this work, and accordingly my invention consists of both the method and the machine which carries it out.

The outstanding characteristic of the machine is also representative of its principal object, the completely automatic riveting of the rim to the wheel disc throughout its entire surface. Other objects I have sought and attained are the following:

A positive and high speed clamping device to hold the disc wheel in the position to be operated upon; a positive, firm and unyielding, yet accurate means of indexing a wheel so clamped from position to position in which rivets are to be applied; a powerful and high speed, yet accurate, piercing device to make the holes for the rivets in a truly radial alignment; an absolutely certain means for feeding rivets to the holes so pierced which will feed rivets as long as there are holes into which may be fed and cease feeding them when the holes are all filled; a powerful high speed, yet accurate riveting mechanism which will effect the riveting operation along truly radial lines with the heads of the rivets snugly in place and the riveted ends coined flatly against the exterior surface of the rim to free the same from objectionable projections; the relation of the piercing and riveting mechanisms to the wheel operated upon and its clamping mounting in such positions that the thrusts and other strains built up in the piercing and riveting operations are taken by the mechanism and not by the wheel body, whereby not only distortion of the wheel body, but correlated unwarranted strains upon the mechanisms themselves are avoided, with great enhancement of the accuracy of the

work and the efficiency and life of the machine; a positive and highly accurate and easily adjustable timing mechanism to correlate the timing of the operation of the various mechanisms used with respect to each other whereby the method of my invention may be fully carried out in a most efficient manner and the highest speed of production attained; the provision of an automatic aligning mechanism in conjunction with the piercing and riveting mechanism which insures, or assists in the insurance of, accuracy of radial alignment of the operations of these mechanisms; the provision of adjustments in connection with each of the aforesaid mechanisms to account for the ordinary wear and grinding of parts, particularly tools such as piercing and riveting dies; to provide for those minor adjustments of the mechanisms themselves to take care of minor variations in dimension of wheels of a given size; to provide for those major adjustments of each and all of the mechanisms engaging the wheel to be operated upon, to operate upon wheels of different size; and finally, to coordinate the entire assemblage of parts and mechanisms in such manner as to attain not only the greatest efficiency of operation, but the highest rate of production consistent with the work which may be obtained from parts well made of a high quality of material. Never before, insofar as I am aware, has this ensemble of objects been attained in a single machine.

In the accompanying drawings I show one embodiment of my invention.

Fig. 1 is a front elevation.

Fig. 2 is a rear elevation.

Fig. 3 is a right-hand elevation.

Fig. 4 is a left-hand elevation.

Fig. 5 is a top plan view.

Fig. 6 is a vertical transverse section substantially on the axis of support of the wheel being operated upon, taken on line 6-6 of Fig. 5.

Fig. 7 is an enlarged vertical axial section of the clamping mechanism per se shown in elevation in Fig. 6 and substantially the same as if taken on line 6-6 of Fig. 5.

Fig. 8 is an enlarged vertical longitudinal

100

section of the piercing mechanism taken substantially on line 8—8 of Fig. 5.

Fig. 8a is a similar view in a slightly different plane showing the parts in a different operating position.

Fig. 9 is an enlarged transverse section of this piercing mechanism taken substantially on line 9—9 of Fig. 8.

Fig. 10 is an enlarged longitudinal vertical section of the riveting mechanism taken substantially on line 10—10 of Fig. 5.

Fig. 11 is a vertical transverse section similar to that of Fig. 9 of the riveting mechanism taken substantially on line 11—11 of Figure 10.

Fig. 12 is an enlarged vertical rear elevation of the indexing mechanism taken substantially on line 12—12 of Fig. 5, looking in the direction of the arrows.

Fig. 13 is an enlarged top plan view of this indexing mechanism together with the clamping and wheel-shifting mechanism.

Fig. 14 is an enlarged vertical rear elevation of the rivet-feeding mechanism taken substantially from line 14—14 of Fig. 5 looking in the direction of the arrows.

Fig. 15 is a top plan view of this mechanism.

Figs. 16, 17, 18, 19, 20, 21 and 22 are details thereof.

Fig. 23 is a vertical rear elevation of a portion of the drive of this rivet-feeding mechanism lying below the body of the machine and substantially from the same point of view defined by line 14—14 of Fig. 5.

Fig. 24 is a similar view of another portion of this drive.

Fig. 25 is a plan view of the portion of the drive shown in Fig. 24.

Fig. 26 is a top plan view of the timing mechanism.

Fig. 27 is a rear elevation of the same.

Fig. 28 is a vertical section of a part of the automatic control mechanism of the machine.

Fig. 29 is a front elevation of an upper portion of this control mechanism found in the upper left-hand corner of Fig. 1.

Fig. 30 is a left side elevation of the same.

Fig. 31 is a vertical cross-section of a brake used in connection with the several mechanisms.

Fig. 32 is a front elevation of the head of the wheel clamp of the clamping mechanism of Fig. 7.

Fig. 33 is a front elevation of the clamping plate coacting with this head.

Fig. 34 shows a front and a side elevation of one of the clamping fingers operated between the head of Fig. 32 and the plate of Fig. 33.

Fig. 35 is a perspective view of a portion of the operating sleeve by which the operating plate of Fig. 33 is carried.

Fig. 36 is a diagrammatic plan showing the symmetrical relation of the rivet pick-up and

the rivet put-in positions and the axis of the pick-up and put-in device of the feed mechanism of Figs. 14 to 22.

Figs. 37 and 38 (on the sheet with Figs. 26 and 27) show details of portions of the timing mechanism.

Referring to the drawings, and first to the general elevation and plan views of Figs. 1 to 5, it will be seen that I have designated the various mechanisms by group letters. The clamping mechanism which mounts the disc I have designated C. The index mechanism, which steps the disc from the riveting position to riveting position, I have designated in general I; the piercing mechanism which pierces the holes in the disc I have designated in general P; the riveting mechanism I have designated in general R; the rivet-feeding mechanism in general F; the wheel-shifting mechanism in general S; and the timing mechanism in general T. The same general designation has been followed throughout the more detailed figures of the drawings whereby they may be the more easily related to the general view.

All of these mechanisms are on or about a common base, B, which is in the form of a casting having a substantially plane upper face. This base B is supported from the floor or other foundation by four (4) legs L, at a vertical height to give the workman the most efficient handling of the wheels which he must place upon and remove from the clamping device C. This operation of placing the wheel upon the clamping device C and clamping it there, and upon the close of the automatic operation upon the wheel, of releasing it therefrom, are the only operations required of the operator.

The clamping mechanism C is centered around the transversely-extending rotatable shaft 10 connected with the indexing mechanism I. This shaft is supported upon the transversely arranged H-shaped frame 11 of the shifting mechanism S, oscillable about the transverse shaft 12, supported from the plane upper face of the base B upon pedestals 13—13 (see especially Figs. 6, 7 and 13). The clamping device per se is shown most fully in Fig. 7 and Figs. 32 to 35 on the same sheet with Fig. 7. Collars 13a removably secured to shaft 12 are provided to variably position mechanisms "C" and "I" to operate on various sized wheels. As here clearly appears, the front end of shaft 10 is provided with an attached flange 14. Secured to it through the intermediary of a pair of adapter discs 15 and 16 is the main clamping head 17 of the mechanism. The clamping head 17 and adapter discs 15 and 16 are bolted or doweled together and to the flange 14 of shaft 10, there being provided suitable registering shoulders and recesses between them.

The head 17 is shown in detail in the section of Fig. 7. It is provided with a shoul-

dered front face 18, the shoulder of which is in the form of a forwardly-projecting boss 26 which receives and centers the wheel by projection into the central aperture of the disc. A section of a wheel of the Michelin type is shown in connection with the clamping head. This type, as at the present time marketed, embodies a pressed steel disc 22 provided with an annular boss 20, and spaced bearing zones 19 and 21, which are respectively borne upon and clamped to the radial face of a hub flange by bolts passed through the boss 20. The perimeter of the radial flange 18 of clamping head 17, is such that it engages the inner face of the disc in the zone 19, slightly outwardly removed from the zone 21.

Engagement in zone 19 with the clamping head 17, is effected through inserts 23 having serrated engaging edges 24 for the purpose of preventing the wheel from slipping. The inserts are circular and attached by central machine screws 25. They provide in effect a three-point bearing for the wheel disc to be clamped in position. The boss 26 of the head 17 is provided with three grooves 27, centered on lines forming chords of the circle of the boss and substantially in the arrangement of an equilateral triangle. In each groove slides a clamping finger 28 having a point 29 adapted to be slid over the outer surface of the boss 20 of the wheel disc and to hold the same in place. These sliding fingers 28 fit snugly against the lateral walls of the groove but have a clearance from the bottom wall of the groove by reason of the offset 30 on the inside of the finger provided between the engaging point 29 and an inside point 31 which rides on the bottom of the groove. Each finger, moreover, is provided on its back with a pin 32 engaged in a slot 33, Fig. 33, in a coacting clamping disc 34 secured on the outer end of an actuating rod 35 extending through the hollow 36 of shaft 10 to the rear of the machine. Clamping disc 34 is secured to the shaft through the intermediary of a sleeve 37 having limited free movement axially of the shaft and connected therewith by a pin 38 in the shaft and a spirally-extending slot 39 in the sleeve. This slot (Figs. 7 and 35) has straight ends, the rear of which is open. Pin 38 passes through rod 35 through the slot and into straight grooves in head 17. The disc 34 not only fits against the shoulder 40 on this sleeve, but is keyed thereto by a key 41 and retained in a keyed position by a nut 42. The sleeve, in turn, is retained on the shaft at its front end by a washer 43, retained against the end of the sleeve and the nut 42 by means of nuts 44. Sleeve 37 has a sliding engagement with clamping head 17. A spring 46 bears against a washer at its rear end, and at the other end against the head of flange 14 on shaft 10, normally biasing sleeve 37

and clamping disc 34 outwardly. Connected with the opposite end of rod 35 is a compressed air cylinder 47 adapted to be actuated to draw the rod 35 inwardly.

The disc 34 is of less diameter than the 70 diameter of the central opening of the wheel. Therefore, a wheel may be freely slipped over it on to the boss 26 and into engagement with the centering inserts 23 of the head 17. When disc 34 is out as shown, the points 29 of 75 clamping fingers 28 are within the circle of the boss 26 as shown in Fig. 7, so there is no interference from them. When rod 35 is drawn rearwardly by the admission of air to cylinder 47, however, sleeve 37 is rotated by reason of the progress of pin 38 in the 80 spiral slot 39 in the sleeve, in turn rotating clamping disc 34 and by reason of the slots 33 in the disc 34 embracing pins 32, moving fingers 28 outwardly to carry their engaging 85 points 29 over the top of the boss 20 into positions to clamp the boss upon the head 17. Further movement of rod 35 as pressure in 90 cylinder 47 builds up to a maximum engages the inner face of disc 34 with the backs of fingers 28, and firmly clamps the points 29 of the fingers upon the boss and, through the boss, clamps the body of the disc to the centering inserts 95 23 of the clamping head 17. So held, the disc cannot slide or turn, and it is accurately centered and held in position. The moment the air pressure in cylinder 47 is released, the spiral spring 46 thrusts sleeve 37 and rod 35 outwardly, reversely moving 100 sleeve 37 and disc 34, first releasing the general pressure of disc 34 upon the boss 20, and then withdrawing the points 29 of fingers 28 from the face of the boss 20. The wheel may then be immediately removed and another put in its place. By suitable choice of 105 adapters 15 and 16, and suitable shaping of the clamping head 17, and perhaps the points 110 29 of the fingers, or the equivalent, any size and type of wheel whatsoever may be similarly clamped in position to be worked upon by this machine.

The compressed air cylinder 47 which actuates the rod 35 is supported concentrically therewith from the rear end 48 of the shaft 10. Support is by means of an adapter 50, threaded directly into the end of the shaft 10 and entering the base 51 of the cylinder. The adapter may or may not consist of an element of the stuffing box of the cylinder. The rod 35 is connected directly with the piston rod 52 of the piston 53 of this cylinder. The compressed air cylinder is of a type commonly used in air-actuated clutches in various classes of machinery such, for example, 115 as turning lathes.

The means by which the cylinder is controlled enters into combination with the general control and timing means of the machine and will be subsequently described.

The index mechanism "I", by which the 120

wheel so clamped in position is stepped from one position to the other, embodies the shaft 10 about which the clamping mechanism is centered and that train of mechanism associated with the rear end of this shaft. The shaft 10 is borne in the frame 11 upon two bearings 54 and 55, the former of which bears against the frontal flange 14, while the latter of which bears against a rear flange 56 of the same shaft. Connected with this rear flange 56 is the index disc 57. This disc is provided in its edge with a number of tapered slots 58 (see Fig. 12) corresponding in number and in position to the number and 15 position of the rivets it is desired to place in the wheel. The disc is removably bolted to the flange 56 whereby discs of other numbers of slots and other positionings suitable for different makes and sizes of wheels may 20 be placed thereon. The body of the mechanism of which the indexed disc is a part is shown particularly in Figs. 12 and 13. Oscillable freely about the projected end 59 of shaft 10 in the rear of the disc 57 is a 25 pending arm 60 which carries at its lower end just outside of the perimeter of disc 57 a pawl 61 in the form of a bell crank pivoted thereto. One arm of this pawl extends laterally of arm 60 substantially along the edge of disc 58 30 and has its end inturned and formed with side walls tapering and complementary to the tapering side walls of the slots 58 of the disc 57. This arm is biased to a position within the slots by means of spiral spring 62, hooked 35 on to the body of arm 60. The bottoms of slots 58 are flat, and the end of pawl 61 is also flat but it does not reach the slot bottom. So, by reason of having been cut off, or by reason of the width of the tapered end 40 having been made sufficiently large to prevent it from reaching the bottom, a perfect alignment of the disc in a given position indexed by the engagement of the pawl in the slot is assured. Still further, the flat inner end 45 of the pawl may ride freely over the flat exterior edge of disc 57 between the slots in progressing from slot to slot.

The outer arm of pawl 61 depends beyond the arm 60 and is there connected by means 50 of adjustable rod or link 63 with an oscillable arm 64 on the projecting outer end 65 of shaft 12 of the shifting mechanism S. This arm 64 is oscillated by a second link 65 connected with a reciprocating slide or cross head 66, mounted in vertically-extended bearings 67 about the driving shaft 68. This slide 66 is reciprocated by means of a cam 69 substantially of heart shape and characterized by a uniform axial width. Such a cam 70 60 is in constant operative engagement on its opposite faces with pins or other followers spaced apart a distance equal to the width of the cam. The slot 71 of a length equal to the throw of the cam plus the diameter of shaft 68 permits free movement of the slide 75

66 about the shaft which pieces it. When so reciprocated, the slide 66, through the train of mechanism 65, 64, 63, 61, will index the disc 57 one slot at a time, provided that the throw is appropriately adjusted through 70 choice of dimension of cam 69 and choice of pivotal connection of links 63 and 65 with the arm 64.

Mounted on the rear face of frame 11 which is of an extensive area, as appears clearly in Fig. 12, are two pawls 72 and 73 adjustive to the ratchet 61. The pawl 73 is merely a resisting pawl, not positively holding the wheel against movement by the ratchet 61, but resisting such movement to a certain degree whereby when the flat end of ratchet 61 on its retrogressive movement is drawn by spring 62 into engagement with the periphery of disc 57, the frictional engagement may not retrogress the disc. To this end, pawl 73 is in the form of a roller mounted on an axis 74 in the upper end of a sliding plunger 75 of rectangular section, borne in a bearing plate 76, bolted to the frame 11, and spring-pressed to the edge of the disc 90 by means of a spiral spring 77. The edges of the slots 58 are slightly chamfered in order to better effect a registry with the circular face of pawl 73.

The other adjunctive pawl 72, however, has a projecting end like the ratchet 61 complementary to the slots 58, yet not reaching the bottom of them, whereby the same effective accurate alignment is attained. This pawl is carried by a plunger 78 bore in a bearing plate 79, and biased to the disc by spiral spring 80. But in addition to this bias, the pawl is mechanically operated. A slot 81 is provided in the rear face of the bearing plate 79, and the pin 82 projected through this slot from the rear face of the stud 78. The pin is engaged in the forked end of a lever 83 pivoted intermediate its ends at 84, upon the bearing plate 79, and provided at its opposite end with a cam roller 85. This cam roller 85 is in the path of movement of the axially adjustable cam 86, carried on the link 63, which actuates the ratchet 61. When in the retrogressive movement of pawl 61, the link 63 is moving rearwardly, the conical forward face of cam 86 engages the roller 85, and oscillating lever 83 retracts the pawl 72 from the indexed disc 57. The disc is thus, by the retrogressive movement of link 63, freed from ratchet 61 and holding pawl 72, but is not freed from the resisting pawl 73. Ratchet 61 retrogresses until it engages in the next slot to the rear, at which time the follower 85 has passed from the conical surface of cam 86 on to the cylindrical surface thereof whereby pawl 72 is retained in retracted position, so when link 63 starts back the engaged ratchet 61 moves the disc clockwise past the indexed position formerly fixed by the pawl 72,

against the resistance of pawl 73 which rides out of the slot in which it was engaged. The reverse movement of link 63 continuing, roller 85 leaves the cylindrical surface of cam 86 and suddenly passes down the conical surface, releasing pawl 72 to bear by its flat end upon the edge of the disc between the indexed slots 58. Then just at the close of the reverse movement of link 63, pawl 72 rides into the next indexed slot 58, and under the urge of spiral spring 80, as the fore edge of the slot reaches the rear edge of the pawl, is projected suddenly and forcibly into the index slot effectually realigning and positioning the indexed disc 57 and consequently the wheel being operated upon in its new position.

By adjusting the plates 76 and 79 upon the face of frame 11, and by adjusting the length 20 63 and the pivotal connection of this link and the link 65 with the lever 64, each of the ratchets and pawls 61, 72 and 73 may be readily adjusted to a different number of indexes and to a different spacing as may be 25 required on various sizes and types of wheels.

The piercing mechanism P is embodied on the left of the wheel so mounted and indexed. It is carried by a frame comprised of front and back pedestal castings 87 and 88, 30 transverseiy of which is arranged the driving part of the mechanism and longitudinally of which are arranged the piercing dies of the mechanism. The dies comprise a female die head 89 having a die aperture 90, and a male 35 die head or punch 91. The female die member is carried on the forwardly projecting end 92 of a hook-shaped forearm 93 of the arm 94, slidably mounted longitudinally in ways 95 in the upper portions of the spaced 40 pedestals 87 and 88. This arm is of generous and sturdy proportion sufficient to take the strain of piercing. The male die 91 is removably mounted or chucked in the fore end of reciprocable arm 96, borne in a slot 45 97 in the body of arm 94. Both arms are removable by removing the tops of the bearings 95. The arm 94 is of substantially uniform width and fits snugly in its bearings throughout its length. Slot 97 is not of uniform 50 width, but is of lesser width at its front end than in its intermediate portion, whereby while arm 96 is borne snugly in the bearings provided by the walls of the fore end of slot 97, its rear end and the actuating mechanism therefor can work freely in the enlarged intermediate portion of the slot as indicated by the clearance shown in Fig. 9. The actuating mechanism for the arms 96 and 94 of the piercing device is clearly shown in Figs. 55 8 and 9.

Referring particularly to Figs. 8 and 8a, it will be seen to comprise a toggle comprised of links 98 and 99 engaging the arms 94 and 60 96 respectively and coupled together by the knuckle joint 100. These toggles break

downwardly to separate the piercing punch 91 and the die 89, and close upwardly to bring them together. Actuation is by means of a vertically reciprocable pitman 100a. Referring to the longitudinal central section shown in Fig. 8a, it will be seen that within the slot 97, the arm 94 is provided with an adjustable block 101 having a convexed head 102, making a bearing with the concaved seat 103 formed in the end of the co-acting toggle link 98. Block 101 is slidably mounted in a way 104 in the rear end of slot 97, has its rear end vertically oblique end engaged by a tapering adjusting wedge 105 vertically adjusted by means of a stud 106 threaded into the body of arm 94, and held against wedge 105 by set screw 106-a in overhang 106-b. By adjusting block 105, the separated distance between punch 91 and its die 89 may be adjusted. Arm 96 on its rear end is provided, also, with a convexed head 107 similar to the head 102 and like the head 102 mating with the concave bearing surface 108 in the coacting toggle link 99. Each toggle link at its upper end 75 is flanked by a plate 109 screwed thereto on each side, and locked in alignment by an inwardly projecting lug 110 at its lower end and overlying the toggle bearings 102-103 80 107-108 at their upper ends. Pins 111 85 passed axially through the toggle bearings within the convexed heads 102-107, and through the overlapping ends of plates 109, bind the toggle bearings together. Thus 90 the toggle arms 98-99 and the piercing 95 mechanism links 94-96, are provided with bearings of great area directly between the members to withstand the high piercing pressure, and the plates 109 and pins 111 are 100 constituted a means to retract the arms 105 94-96 after the piercing operation.

The knuckle joint 100 between links 98-99 and the pitman 100a is of peculiar construction. Opposite halves 112-113 of the toggles are provided with convexed ends complementary to the entire concave end 114 of the pitman 100a. The convexity of these half ends of the toggle links is carried through the greater part of a circle of uniform diameter. The remaining halves 115-116 of links 110 98-99 are cut back for the diameter of the convex end and at the bottom of the cut back portion are formed complementally concave to the convexed half of the opposite link respectively as indicated in detail in Figs. 9 115 and 8a. On opposite sides of the pitman 100a are provided plates 117 similar to plates 109 of the links 98 and 99 aligned by bottom lugs (not shown) let into the body of pitman 100a and bolted to the pitman by bolts 118 as 120 shown in Figs. 8 and 9 and overlapping the knuckle joint 100. Pin 118-a is passed axially through this knuckle joint within the bodies of convexed halves, 112, 113 of links 98-99 and through the ends of plates 117. 130

- Thereby as in the case of the toggle links and the piercing arms, here the pitman and the toggle links are provided in the knuckle joint with directly engaged surfaces of the parts 5 constituting bearings of large area through which the piercing pressures are transmitted and with a means of breaking the toggle comprising the pin and the opposite plates 117 connecting in common with all the parts.
- 10 The pitman 100a is reciprocated substantially vertically by means of cams 119, 120 revolved by a power driven shaft 121. Cam 119 engages a central cam follower roller 122, journaled directly in the lower forked end 123 of the upper portion or head of the pitman 100a. There are two cams 120, one on each flank of pitman 100 and each of which engages a cam follower roller 124 journaled on the corresponding downward extension 15 125 from the corresponding fork 123 of pitman 100a. These extensions are U shaped, the arms of the U being bolted to the sides of the fork 123 as shown in Figs. 8 and 9, and the cam followers 124 being carried by the 20 bight of the U, the arrangements being such that the U shaped extension encompasses the shaft 121 and is of sufficient dimension to permit the pitman to be reciprocated up and down about the shaft without interference.
- 25 30 The pitman is borne in upper and lower slide bearings 126 and 127 respectively formed in the inner sides of the flanking frame members 87 and 88 (Fig. 9), jointly by means of rollers 128 carried on lateral extensions of the pin 129 by means of which cam roller 122 is carried and the axially extending lower cam rollers 124. The lower guide way 127 is substantially truly vertical and the axis of cam and guide rollers 124 is 35 permanently in the substantially true vertical alignment with the axis of the fixed drive shaft 121. The axes of guide rollers 128 and knuckle joint 100 are likewise in such alignment when the toggle is broken and the die 89 and punch 91 are separated as shown in Fig. 40 45 50 55 60 65 9. But the upper guide ways 126 are inclined to the right to a substantial extent as clearly indicated in Fig. 8a, with the result that when pitman 100a is moved upwardly, the pitman is bodily moved to the right about the axis of cam and guide rollers 124, thus carrying to the right not only the knuckle joint 100, but also both the die 89 and the punch 91. The function of this will presently be apparent.
- Pitman 100a is moved upwardly by the engagement of cam 119 with the central cam follower 122. This cam is provided with an abruptly rising surface 130 through which the pitman 100a is raised rapidly for a certain distance. This distance is approximately that which, due to the combined joint movement to the right occasioned by the incline of the guide 126, and the coincident and proportional closing movement of the toggle 98, 99, will bring the punch 91 into substantial contact with the rim 131 of a wheel being operated upon. The parts then occupy the positions shown in Fig. 8a. The guide rollers 128 have then reached the upper ends of the guides 126. In this upper portion the guides are widened apart as shown in detailed Figure 8a. Thereby when the die 89 and punch 91 are both engaged in operating upon the wheel, the pitman floats freely on knuckle joint 100 and cam and guide rollers 124, the axes of which lie on a line determined by the engagement of punch 91 and die 89 with the wheel, and thereby the body of the wheel is not subjected to any of the 70 75 80 85 90 95 100 105 110 115 120 125 130 135 140 145 150 155 the completion of the piercing operation, the cams 120 engage the cam followers and guides 124 upon the advance of retracting face 136 and retract pitman 100a, and through its retraction break the toggle 98 and 99 set by the piercing cam 119, retracting the die 89 and the punch 91 from the work. This can easily be followed from Fig. 8a. Upon reaching the extreme retracted position, the followers 124 pass on to the extended circular face 137 of cams 120, upon which face these followers ride during the remaining operations of the machine at large and until it is time to perform the next ensuing piercing operation. At this time the followers have reached the reentrant faces 138 of cams 120 which drop sharply away toward the hub of the cam substantially symmetrical with respect to the face 136, and complementally to the abrupt actuating face 130 of the piercing cam 119 which engages the upper follower 122 just at this time.

The metal punched through the rim in the piercing operation is punched into the hollow interior 139 of the die 89. This interior has near the mouth of the die, a restricted throat 140 which restricts, to a certain degree, the free passage of the punchings through the hollow of the die. Jointly, by reason of the forming over of one thickness of metal upon the edge of the other, due to the piercing operation of the punching die 91, and to its restriction 140 in this passage 139, the punchings come through sticking together much in rod-like form. In continuation of the hollow 139, I provide a hollow flanged bushing 141 in the rear end of the arm 92. Obliquely of the end of the opening 142 in this bushing, I provide a pin 143 in such position that the rod-like series of punchings is engaged as it emerges from the end of the bushing, and the punchings are broken apart. They drop into a discharge conduit 144, connected with a bushing 141 by a casing 145, and are discharged by conduit 144 to some point beneath the machine.

Both the punch 91 and the die 89 are exchangeably mounted in arms 92-96 respectively, whereby either or both of them may be freely removed and replaced for repairs and regrinding, and for the substitution of tools of different sizes to make piercings of different diameters and to operate upon wheels of different sizes. Merely by changing the relative lengths of the punches 91 and dies 89, the position of the normal gap between them radially of the wheel structure may be changed, and the piercing mechanism adapted to operate upon a wheel of corresponding diameter.

Next in order in serial arrangement anti-clockwise, around the periphery of the wheel, is a mechanism "F" for feeding the rivets into the pierced holes. The wheels are stepped by the index mechanism, "I", previously de-

scribed in an anti-clockwise direction looking from the front of the machine and hence the anti-clockwise arrangement of the series of mechanisms described. This feeding mechanism "F" comprises a box-like container 146, carrying a supply of rivets, a feed trough 147 by means of which an extended series of rivets in upright position are carried from the container to a determinate feeding position to one side of the wheel being operated upon, an up-righting mechanism designated generally by 148, by means of which the rivets in bulk are progressively up-righted and discharged into the feed trough 147, and a pick-up and put-in device designated generally by the numeral 149 and the function of which is to pick up the rivet from the determinate feeding position at the end of the trough 147 and place it in position in the pierced hole in the wheel rim.

The reservoir 146 is a box-like structure mounted upon the pedestal 150 on the plane upper face "B" of the base of the machine horizontally to the rear of the piercing mechanism "P" and to the left of the clamping and index mechanism "C" and "I". In general, it together with its trough is arranged in a vertical plane oblique to the plane of mounting of the wheel being operated upon. The trough 147 is fixed to it, as is also the up-righting mechanism 148, and the assemblage is vertically adjustable by means of the vertically adjustable clamp 151 by means of which it is supported upon the pedestal 150.

The up-righting device comprises an oscillatable trough extension 153, journaled in front end of the box 146 upon a transverse axis 154 and projecting lengthwise within the body of the box and oscillatable in a vertical plane therein through an angle which carries its trough shaped upper edge downwardly into a mass of rivets within the reservoir 146 near the bottom thereof and then upwardly until the trough shaped upper edge is substantially in rectilinear alignment with the projected line of the feed trough 147 with which its pivoted front end communicates directly. The trough 147, and the oscillating extension 153, are of the same shape, having a body of a width nicely accommodating the shanks of the rivets, but not admitting the heads thereof at any point in the lengths of the members whereby rivets caught in the extension trough 153 on its upward movement through the mass in the reservoir 146 if they are upright fall by their shanks into the trough. If they are not upright they ride obliquely of the top of the trough supported by their heads, ends or sides in various positions. Toward the outer end of extension 153 from the pivotal axis 154 is a fixed gate

155, fixed to the body of the reservoir 146 and projecting through the trough to the upper edge by way of a slot 156 in the front end of the trough. The upper end of this gate 155

155 is sharpened or pointed and is located upon the line which the upper edge of the trough extension 153 occupies when it is at its upper extreme of movement. Also carried fixed to the reservoir 146 is the coating gate member 157 in the form of an upright plate bearing a removable slide 158 in the bottom of which is a slot of a form corresponding to the form of an uprighted rivet and slightly greater than the rivet in dimensions. The bottom of this slot is closed by the upper edge of the gate member 155 and completes the outline of an uprighted rivet. Only an uprighted rivet can pass through this gate. 15 All the rivets in the trough extension 153 slide downwardly under the action of gravity when the trough is in its elevated position and those rivets lying immediately adjacent to the gate and also in an uprighted position, pass through the gate as the trough extension pauses in its upward movement. Those not uprighted lie more or less crosswise or endwise against the gate upon their ensuing downward movement through the trough. 20 They are pushed away from the gate and out of the trough by the downwardly widening gate member 155.

Those rivets that pass through the gate 155, 157, slide freely from the front end of the trough extension 153, and into the trough 147 where they lie in series drawn by gravity against the terminal feed position 160. This terminal feed device is constituted by a closure 161 of the end of the trough 147. The 25 top of the trough is here deflected at an angle to the body substantially to a horizontal plane. Its side walls are thin as shown in Figs. 18 and 21, and, surrounding the shank of the rivet in the feeding position 160 the top 30 of the trough is of less width than the extreme diameter of the head of the rivet as indicated at the point 162 (see Fig. 21). The end of the trough is steadied or supported from the upper face of the base "B" by means of the 35 upstanding support 163. This end of the trough is adjustable on support 163 by means 40 of the clamping device 164 to regulate the vertical height of the feeding position 160.

The pick-up and put-in mechanism 149 is 45 supported upon and operated by a vertically extended shaft 165 having a combined movement of vertical reciprocation and oscillation about its axis. Support is by means of a pedestal 166, projected through base "B" 50 from the lower side (see Figs. 23 and 14) and secured to the base by a bottom flange 167. The relation of the axis of shaft 165, the axis of feed position 160 and the axis of that piercing 188 in the wheel being operated upon 55 lying vertically in line, in any indexed position, with the axis of the clamping means "C", is an isosceles triangle, the base of which is the line connecting the axis of the feed position 160 and the axis of the pierced hole, 60 (see Fig. 36). A pick-up arm 168 at the

upper end of shaft 165 arranged radially thereof, in its oscillations, therefore successively intersects the axis passing through position 160 and the axis of the pierced hole 188 in line with the axis of the clamping mechanism. This arm is adjustably clamped by split collar 169 upon the shaft 165. A forked shoulder 170 is angularly fixed upon the upper end of shaft 165 by a tapered bolt 171 passed through its body and engaging the elongated flat of the upper end of the shaft 165. It may be freely adjusted vertically as may also be the pick-up arm 168. Its forked ends are provided with set screws 173 which engage on opposite sides the arm 168 and by the relative movement of which (after the loosening of collar 169) this arm may be relatively angularly set with respect to the forked shoulder 170.

The forearm 174 of arm 168 is connected with it by a transverse elbow joint 175 breaking upwardly under pressure, but precluded from breaking downwardly by the abutting walls 176. The forearm 174 is retained normally in its lower position by means of an adjustable spiral spring 177. At its outer end it is provided with two downwardly extending fingers alike in all essential respects and designated 178. These fingers are supported by a vertically extending substantially cylindrical wrist member 179 guided in the vertical aperture 180 at the end of arm 168 and secured to forearm 174 by a pivot pin 181. The body of the wrist member 179 which passes through aperture 180 is reduced, and between the end of the arm 168 and the shoulder formed by the reduction, is surrounded by a spiral projecting spring 182 of less strength than the spiral spring 177 by means of which the forearm is held in its lowered position. The lower end of the wrist 179 is transversely slotted all the way through the shoulder and it is within this slot that the fingers 178 are located. The fingers are angular in shape having one branch horizontally extending through the slot and the other vertically extending and projecting through the mouth of the slot at the bottom. They are pivoted to the wrist by pins 183 passing through the oppositely disposed outer ends only of the respective transversely extending branches. Their knuckles each bear against the collar 184, borne downwardly by the spring 182 against the shoulder, and the tips 185, therefore, of the fingers are pushed together. The tips are sharpened on their adjacent points so that each presents a sharpened end projecting toward the axis of the wrist 179. Midway between the fingers and on the vertical axis of the wrist, is a transversely extending pin 187 fixed in the body of the wrist. This pin 187 is at a height above the sharpened points of the fingers slightly greater than the height of the rivet head, and the upper edges of the tips of the

fingers are shaped complementally to the shape of an upright rivet head on its outer and under sides.

So organized, the pick-up and put-in mechanism through an oscillation of the shaft 165 to a position in line with the axis of feed position 160 (Fig. 36), may then be slid downwardly with the wrist axis and the position axis in coincidence until the tips of fingers 186 engage over the head of a rivet in position 160 by reason of the tapered walls 182 of end of trough 147 slid over and under the head of the rivet in position; may then be raised vertically upward with the axes still in coincidence to a position in which the wrist and fingers, when oscillated, will clear the rim of the wheel being operated upon, may then be oscillated angularly to cover the angle of the apex of the isosceles triangle of the axes; and may then be again lowered vertically on the axis of the pierced hole 188 in which the rivet is to be placed, and when so lowered will thrust the shank of the rivet picked up into the open pierced hole. The tips of its fingers 186 will engage the flange 132 of the wheel being operated upon and by reason of the pivoting of the fingers on pins 183 displaced laterally of the tips, spread the tips apart to release the head and shove the rivet down by the engagement of the pin 187 with its head. Shaft 165 may then be raised and the path of the mechanism just described retraced for an ensuing pick-up and put-in operation, but in such movement the rivet put in will not again be picked up for the simple reason that the projecting ends of the fingers are below the sharpened inside tips 185 and the tips are retained in an elevated position above the under sides of the head of the rivet placed in the pierced hole. An inspection of Fig. 20 will make these points clear.

Over movement in the vertical direction in either the pick-up position 160 or the put-in position 188, after the spring 182 has been flexed to its limit and fingers 178 are open to the fullest extent, is taken by the forearm 174 which moves upwardly against the tension of the forearm spring 177. Such accommodation of over-movement is of particular advantage in that it insures reliability, irrespective of slight differences of dimension of the machine or of the work being operated upon. Beyond this, however, when the put-in position 188 is occupied by a pierced hole in which a rivet has already been placed, as is the case during the portion of the operation of the wheel due to the necessary serial placement of the several mechanism about the periphery rather than the grouping of all of them at a single point, the engagement of the end of the shank of a picked up rivet with the head of the rivet already in position, thrusts a picked up rivet against the pin 187 and through it thrusts the

forearm upwardly without opening the fingers 178, without dislodgement of the picked up rivet and without damage to the feeding mechanism "F". This picked up rivet is then carried back to the pick-up position 160 and there, instead of picking up a new rivet, the shank of the rivet already picked up engages upon the head upon the rivet in position 160 with the result of movement of the forearm 174 precluding the opening of fingers 178, and retaining the picked up rivet in their grasp to be represented repeatedly to the wheel being operated upon until an unfilled pierced hole occupies the put-in position 188. Thus is the feeding operation governed by the empty or the full condition of the holes in which rivets are to be put.

The mechanism is carried through these operations by the actuating devices shown more particularly in Figs. 23 to 25. The devices shown in Figs. 24 and 25 operate the up-righting mechanism 148. The shaft 189 extends transversely of the under side of the base "B" and is supported therefrom by the bearing brackets 190, see Fig. 6. The axis of the shaft lies in a plane passing between the pick-up and put-in mechanism 149 and the up-righting mechanism 148. It carries an eccentric 191 upon which operates an eccentric strap 192 closed about the eccentric 191 so as to be self-aligning therewith. This eccentric strap 192 is provided with a pair of ears 193 between which is pinned oscillatably a rod 194 having a ball joint connection 195 with the lower arm 196 of a bell crank 196 and 197, oscillatable about an axis 198 constituted by a shaft 199, pinned to bell crank and in turn journaled in the lower end of the bearing block 200, carried on the under side of the base "B". The arm 197 of this bell crank is connected by a longitudinally adjustable link 201, with the oscillatable trough extension 153 of the up-righting mechanism 148. Through this train of actuating devices, the trough extension 153 is oscillated in a manner previously described without lost motion, and with a high efficiency in spite of the oblique disposition of the feeding mechanism "F" at large, since the manner of connecting the link 194 to its adjoining parts makes full provision for each change in angularity occurring during the oscillatory movement of the bell crank 196 and 197.

All devices of Fig 23 are provided for carrying out the combined reciprocatory and oscillatory movements of the shaft 165. These comprise a pair of cams 202 and 203, formed as a single member 204 upon the same shaft 189 from which the up-righting mechanism 148 is operated. But these devices are in the main on the right of the shaft instead of the left as in the case of the up-righting mechanism. The cam 203 is that which reciprocates the shaft 165 on its vertical axis. It is

- in the form of an elliptical groove on the front face of the cam member 204, symmetrical with respect to the axis of the shaft 189. Engaged in it is cam follower 205 on one end of a cam lever 206 journaled intermediately in bearing 207 carried by base "B" and engaging at its opposite end 208 with the flanged collar 209 secured on the lower shouleder end of shaft 165 by means of nut 210.
- 5 For each revolution of shaft 189, shaft 165 is reciprocated vertically twice. Cam 202 is in the form of a shield shaped groove in the opposite face of the member 204. In it is engaged the follower 211, secured intermediately of the opposite ends 212, 213 of cam lever 214, pivotally mounted at its lower end 212 upon a pedestal 215 depending from the base "B", and connected at its upper end 213 to the universally jointed link 216, which in turn connects with an arm 217, keyed by the extensible spline connection 218 shown in Figs. 14 and 22 to shaft 165. These devices oscillate shaft 165 once for each revolution of shaft 189. Cams 202, 203 are angularly so related to each other that they are symmetrical about the minor axis 219 of the elliptical cam 203. The dimension of the major axis of the cam 203 and the dimension of the active face 221 of cam 202 are respectively such that the total range of reciprocation of shaft 165 between the horizontal plane of the pick up position 160 (which is the same as that of the put in position 188) and the upper extreme of movement, will give all the rim clearance desired for operation in connection with any size of wheel. The range of oscillatory movement is approximately equal to the apex angle of the isosceles triangle of the axes of the mechanism previously referred to.
- 30 Variations as outlined hereinbefore are taken care of effectually by means of the various springs in connection with the pick up arms, and in addition may be taken care of by the set screws 173 in the forked shoulder 170.
- 35 Thus for each complete oscillation of shaft 165 through the apex angle of the triangle, it is reciprocated twice, once to pick up a rivet from position 160 and once to put in a rivet in position 188, and each time accurately in coincidence with the axes of these positions. The arm 217 is retained in proper relative position to link 216 by the engagement of its collar 221 in the recess on the under side of the flange 167 of pedestal 166 in which engagement it is retained by a bolt 222 screwed or otherwise secured to the other side of the flange. A minor adjustment of the limits of the oscillatory movement, and positive definition of these limits is obtained by the device
- 40 shown in Figs. 14 and 22. This comprises an extension 223 for the outer end of pedestal 166, provided with two radially extending ears 224 in which there are mounted set screws 225, coacting with the opposite faces of an arc shaped depending lug 226 carried

by the collar 227 adjustably clamped by means 228 upon the body of shaft 165. The angle subtended by radii passing through the ends of the adjusting set screws 225, minus the arc subtended by the lug 226, is approximately equal to the apex angle of the isosceles triangle of the axes of the mechanism, whereby the limitation of the oscillatory movement between the pick-up and put-in axes 160 and 188 is assured.

The rivets placed in position 188 after the wheel being operated upon has been indexed through an angle approximating 90°, as clearly appears in Fig. 10, are riveted in place by the riveting mechanism "R". This mechanism is somewhat similar in general appearance and general manner of operation to the piercing mechanism "P" as can be readily discerned by examination of Figs. 9, 10 and 11. But it differs not only in the operation performed, but substantially in a number of respects of the movements and the mechanisms by which they are secured.

The rivets are retained in their placement in the pierced holes by means of a fixed spring retaining strip 227a, arranged on an arc closely adjacent the inner surface of the flange 132 and held in this position by two brackets, the one 228a of which is bolted to the outer face of the frame 11 which supports the clamping mechanism "C", and the other 229 of which is supported from the same face at a point closely adjacent to the under side of the riveting mechanism per se. This strip 227a bears against the heads of the inserted rivets as they pass from the position 188 and prevents any substantial movement out of the pierced holes. However, the arc is not closely contiguous to the heads throughout its length diverging therefrom slightly in one position of the rim to an extent and for a purpose which will presently appear.

The riveting position is designated 230. In this position the head of the rivet is engaged by an anvil member 231 and the shank of the rivet by a riveting punch 232. The anvil 231 is shaped complementally to the head of the rivet, while the head of the punch 232 is given that shape preferably substantially flat to which it is desired to coin the end of the rivet shank when it is forced into the countersink of the outer end of the pierced hole. Both the anvil 231 and the riveting punch 232 are removably secured to the members which support them as indicated in the case of the punch by bolts 234, whereby they may be readily removed and replaced by similar members adapted to act upon wheels of different sizes and types.

The anvil 231, is fixed in position, being carried by the front end of the hook shaped arm 235 which arm is fixed in position by bolting upon the tops of a pair of flanking body castings 236-237 alike in all essential respects to the castings 87 and 88 which con-

stitute the supporting frame work for the piercing mechanism "P". The punch 232, is carried in the socketed outer end of the reciprocating arm 238, slidably mounted in bearing 239, formed interiorly of the body of the front end of the fixed arm 235. Intermediate the ends thereof the arm 235 is apertured at 240 just as is arm 94 of the piercing mechanism. At the opposite end of slot 240 and in line with the bearing 239 is a bearing 241 which carries slidably mounted a normally fixed sliding block 242. This sliding block has its rear end tapered obliquely downward and to the right and seated against an adjustable wedge 243, the vertical adjustment of which is controlled by a screw 244, whereby the block 242 may be projected forwardly by adjusting the wedge downward. Block 242 is secured in any one of the adjusted positions by an obliquely positioned set screw 245. Cap plates 246 retain the slides 238 and 242 in their places.

Interconnecting the inner convexed ends 247, 248 respectively of the slide 238 and the block 242, are a pair of toggles 249, 250, the ends of which complementary to the convexed heads 247 and 248 are formed concave. The opposite ends of these toggle arms 249, 250 are in turn formed one half 251, convex, and the other half 252, concave, and the concavities and convexities given the same diameter whereby they mutually engage and bear upon each other as clearly indicated in Fig. 11. Both of the convexed ends 251 bear upon the complementary concave upper end 253 of a pitman 254, operated from the same drive shaft 68 from which the index mechanism "I" is operated. In this manner when the toggle 249 and 250 is operated to closed position by an upward movement of the pitman 254, the associated parts bear directly upon each other through bearing surfaces of substantial proportions amply sufficient to develop the maximum pressures desired for riveting. The toggle is broken and the parts returned to the normal position from the riveting operation by means of end plates 255 at the upper ends of the toggle arms and similar end plates 256 at the upper end of the pitman. These are in all essential respects similar to the end plates 109 used in connection with the toggle devices of the piercing mechanism "P". They are bolted to the opposite sides of the arms and pitman, are provided at their lower ends with an aligning means comprising a socketed lug 257, transversely of the member with which they are associated, and at their upper ends are pierced by pins 258 which pass also through the convexed ends of the members on axes coincident with the axes of the joints of which they form a part.

The pitman 254 is reciprocated by an eccentric 259 on shaft 68 with which it has connection through eccentric strap 260. With this relation of parts, by reason of the con-

stant throw of the eccentric 259, the riveting punch 232 has a constant length of stroke. The limit of this stroke, however, may be regulated to a nicety by an adjustment of the wedge 243. This adjustment is made such that when the rivet is pushed head down to the flange 132 of the wheel being riveted, the head of punch 232 at its inner extreme of movement rivets the projected shank of the rivet down into the countersunk outer end of the pierced hole in which the rivet lies, coining the head of the shank to fill this countersunk portion snugly and to provide an outer riveted end substantially flush with the outer surface of the rim itself.

Coordinating the operations of the piercing and riveting mechanisms, and with them carrying out that part of the method of my invention which consists in floating the wheel being operated upon upon the operating tools, thereby eliminating strains in the wheel or in the mechanism, is a shifting mechanism "S" which acts upon the work being operated upon to shift the same from a piercing position to a riveting position. This shifting mechanism "S" acts upon the work through the intermediary of the clamping mechanism "C" and particularly through the supporting frame 11 of that clamping mechanism. This mechanism is shown in detail in Fig. 6.

The shifting from piercing position to riveting position or vice versa is an oscillatory movement of comparatively small degree about the shaft 12, from the position shown in full lines on Fig. 10, to the position shown in dotted lines. The position shown in full lines is the riveting position and that in dotted lines the piercing position. This latter corresponds to the position shown in full lines in Fig. 8. This movement carries the centre of the clamping mechanism and hence the centre of the work being operated upon from the piercing position 262 (Fig. 10) over the arc 265, to the riveting position 261. It carries the pierced hole which is to occupy the riveting position 230, from a position spaced away from the die 264, of the anvil 231, as shown in dotted lines in Fig. 10 over the arc 265, concentric with the shaft 12 into substantial, though not entire contiguity to the face of the anvil die 264 as shown in full lines in that figure. Through this movement the body of the wheel being operated upon, and the clamping mechanism "C" by which it is supported, is floated upon the head of the rivet in position 230. This is to say that the entire weight of the body of the wheel and the substantial portion of the weight of the clamping mechanism "C" and the indexing mechanism "I" are thrown by gravity about the axis 12 upon the head of the rivet to be operated upon. A counter-active spring 266 (Figs. 6 and 12) may be adjusted to bring more or less of this weight upon the head

120
125
130

- of the rivet when the axis of the work is in its lower position, designated 261. The result is that substantially the entire thrust of the riveting operation is taken up against the face of the die 264 of the fixed anvil 231 and is not transmitted to any degree to the structure of the wheel and it is impossible to distort the wheel to the slightest degree during the riveting operation. This method also enables the machine to operate upon wheels irrespective of the slight variations in dimensions, enables the projecting rivet heads to be freely passed through the riveting position 230 without moving the die 264 and thereafter snugly cupped therein, and still further enables the work to be indexed without interference between the rivet heads and the tools which operate upon them. There are yet other advantages it is not necessary to recite to justify the method and construction used.

The mechanism "S" by means of which this movement is carried out comprises a bell crank 267, borne on a stub shaft 268, and actuating by the bearing of its upper and horizontal branch 269 upon a plate 270 affixed to the transverse web 271 of the frame 11 of the clamping mechanism "C". The lower and depending arm 272 of this bell crank is provided on its end with a cam follower 273 actuated to oscillate the bell crank 267 by a cam 274 carried by a short cross shaft 275, rotated by beveled gears 276 from the driving shaft 189 of the pick-up and put-in mechanism previously described. This drive shaft extends transversely of the base "B" of the machine below the same as heretofore described. The bell crank 267 is pivoted above the base, but has its lower arm 272 projected through slot 277 for the purposes described. The cam 274 is provided with a face 278 concentric with shaft 275 and of relatively small diameter which permits follower 273 to ride in a lowered position in which the work is lowered to the full line position of Fig. 10 through a portion of the revolution of shaft 275. An adjoining abrupt lifting face 279 then engages follower 273 to lift the follower and through the train of mechanism described to lift the work to the dotted line position of Fig. 10 and the full line position of Fig. 8. In this position it is held by its engagement upon the extended concentric cam face 280. Between the surface 280 of the lifted or piercing position and the surface 278 of the lowered or riveting position, there is an abruptly declining substantially radial face 281 which when it reaches the follower 273, permits the wheel to drop more or less quickly under its own and its supporting mechanisms' weight to the lowered or riveting position. In such a drop it is cushioned by the cushioning spring 266 clearly shown in Fig. 6. This cushioning spring is adjustably

housed in a bushing 282 and acts upon the frame 11 through the pin 284.

Preferably the axis 12 about which this shifting movement takes place is located in a vertical transverse plane passing midway between the engaging ends of the die 264 and the riveting punch 232 (Fig. 10) when they are spaced apart their maximum extent. This provides a substantially rectilinear movement of the riveting position 230 in the instance of a wheel of average diameter, and therefore common for wheels of all diameters within the capacity of the machine, a minimum of displacement of the rivets in the relatively fixed anvil die 264. Moreover the axis of the riveting mechanism designated generally 286, instead of being horizontal, is arranged on a slight inclination downwardly and inwardly toward the work, so that it lies, when the work is in its lowered or riveting position, on a true radial line which coincides with the axis of the pierced hole and rivet in position 230, and passes through the then center 261 of the work being operated upon. Thereby in the riveting of the work to secure the advantages herein before set forth, the riveting operation is yet performed on a truly radial line as is proper to secure the best results.

The several mechanisms so far described are commonly driven from the main longitudinally extending drive shaft 287, journaled in bearings 288, projected rearwardly from the rear face 289 of the base "B" of the machine. This shaft is driven by an electric motor 290 or in any other suitable manner and at an appropriate speed. It drives the left and right transverse shafts 121 and 68 respectively of the piercing and riveting mechanisms "P" and "R" through the intermediary of similar worms 291 and worm gears 292. Gears 292 are connected to the respective shafts through axially operable jaw clutches 293 and 294 respectively, the jaws of which are so related that they are substantially free from lost motion. The left hand clutch 293 of the piercing mechanism is operable by means of operating lever 295 connecting with the operating bell crank 296 of longitudinally extending operating shaft 297 by means of a link 298. Crank 296 has a forked connection with the clutch. The right hand clutch 294 is similarly operable by means of a lever 299, a bell crank 300, an oscillatable bell crank shaft 301 in longitudinal extension of the shaft 297 and a link 302. The bell cranks are keyed to the respective portions of the shafts 297 and 301 whereby they may be operated whenever the shafts are oscillated. When the clutches are closed, the mechanisms operated from the shafts 121 and 68 are operated in the manner described, yet when they are opened, the operations of these mechanisms cease, (see Figs. 1, 3, 4, and 6).

The transversely extending shaft 189 from which the feeding mechanism "F" and the shifting mechanism "S" are operated through the trains described, is also operated from the main drive shaft 287; in this case through a worm 303 and the worm gear 304. Worm gear 304 is, as in case of the other mechanisms, coupled and uncoupled to the shaft which it drives, in this case by means of a jaw clutch 305 of similar type to those described. A depending U shaped bracket 306 serves to journal the outer end of shaft 189. This clutch is operable from the right hand section 301 of the operating shaft 297—301 by means of a crank arm 307 on this portion of the operating shaft connected by a link 308 with the arm 309 of a bell crank 309—310 journaled in the bracket 311 overlying the drive shaft 287 and projecting the bell crank in a position to enable its forked arm 310 to engage the movable member 313 of the clutch. This clutch 305 is also of an axially shifttable square jawed type, free from substantial lost motion.

This entire group of mechanisms are coordinated in their coaction upon the wheel being operated upon by the timing mechanism. This mechanism designated "T" is shown particularly in Figs. 26 and 27 which are respectively horizontal plan and rear elevation of this mechanism. The mechanism acts in the main through the sections 297—301 of the actuating shaft of the main clutches 293—294 and the subordinate clutch 305 just described. Its central element is a disc or table 314 revolving above the base "B" and the shaft 297—301 on an axis located inside of the machine but closely adjacent to the shaft 297—301. The sections 297 and 301 of this shaft are independently journaled on the base "B" and the timing disc 314 carries device 315 which coacts with arm 316, carried by section 297 and device 317 which coacts with arm 318 carried by section 301. The two sections of the shaft are coupled together by a jaw coupling 319 having a lost motion such that the shaft 297 may be operated independently of shaft 301 to release the clutch controlled by it, but the direction of operation of the coupling 319 is such that when shaft 301 is operated, it also operates shaft 297, and both the clutches controlled by these sections are operated. This clutch is shown in dotted lines in the plan view of Fig. 26 and in elevation in Fig. 27.

The disc 314 is carried on a spindle 319a, journaled vertically in a pedestal 320, carried on the upper side of the base "B" just in front of the shaft 297—301. The journaling is by means of a bushing 321 upon which the disc 314 is directly mounted. Above the disc 314 there is clamped to the upper end of the spindle 319—a an arm 322. The outer end of this arm is provided with a socket 323 in which there is mounted a pin 324 projected

outwardly of the socket in the counter clockwise direction by means of a spiral spring 325. The pin is prevented from entirely leaving the socket by any suitable means and is normally projected such a distance 70 from the arm that its head is spaced from the adjacent face of the arm. Mounted on the face of the disc, and occupying a position in line with pin 324 when engaged thereby, is an adjustable set screw 326 constituting an 75 abutment engaged by the head of the pin 324. The screw is carried in a block 327, bolted to the upper face of the disc. Through these means, the disc is rotated when the spindle 319—a is rotated, (see Figs. 26, 27 and 6). 80

Projecting through the base "B", the spindle 319—a on its lower end is provided with a worm gear 328 engaged by a worm 329 on the transverse shaft 189 whereby whenever this shaft is rotated, the spindle is rotated, 85 and the disc 314 is revolved. The mechanism by means of which this shaft is rotated is shown in Fig. 6 and has already been described. It includes clutch 305 shown particularly in Fig. 6, and this clutch is closed, as 90 has been said, whenever the clutch 293 of the riveting mechanism is closed.

The devices 315 and 317 which operate the arms 316—318 are in the form of dogs carried by the outer portions of disc 314. The outer ends of arms 316—318 are formed as followers engaged by these dogs. Dog 315 and the follower 330 of arm 316, lie on a circle of revolution 331 within a second circle of revolution 332 upon which lie dog 317 and the follower 333 of arm 318. Consequently each dog actuates its associated arm without interference from the other. The worm gearing 328—329 by means of which spindle 319—a is driven, is of such ratio as compared with the driving means of the index mechanism "I", that disc 314 of the timing mechanism "T" makes a single revolution, while the wheel being operated upon is indexed through one and one-half revolutions. In the position in which the parts are shown, dog 317 has just passed over the follower 333 of arm 318 and operated shaft 301 to stop the riveting mechanism "R" and with it to operate clutch 305, also to stop the timing mechanism "T". The parts are therefore idle. In this position, dog 315 is adjusted angularly with respect to its follower 330 of arm 316 so that they are spaced apart approximately 120° as indicated. Then under the rotation 105 of timing disc 314, dog 317 rotates a full revolution before reengaging its follower 333. The dog 315 rotates only 240° or two-thirds of a revolution before engaging its follower 330. Thus the piercing mechanism 110 is discontinued through the action of this control shaft 297 and the resultant opening of its clutch at the close of a complete revolution of the wheel being operated upon. The riveting mechanism "R" is continued in op-

115
120
125
130

eration for another one-half revolution of the work being operated upon. When either dog 315 or 317 engages its follower 330 or 333, the pin 324 yields until a certain pressure is built up on spiral spring 325 sufficient to suddenly project the dog engaged over its follower. This insures a non-interference between the dogs and their followers when it is desired to start the machine. Overlying the dog 317 is a supporting roller 384 which bears down upon its top to prevent deflection of the disc 314 under the heavy operating pressure required to throw the clutch connected with the riveting mechanism. This is not thrown during the last riveting operation, but just following the last operation, but nevertheless, the fact that arm 318 lies on the near side of the shaft 301, causes this pressure to be an unusual one.

This timing mechanism "T" like the other mechanisms, has its operation initiated through the control mechanism at large. This control mechanism comprises both manual and automatic means. The foremost manual means is the single foot lever 335 (Figs. 1, 2 and 4) by means of which the entire operation of the machine may be initiated. The end of this foot lever lies at the front of the machine near its centre and immediately below the wheel clamping position whereby an operator putting a wheel in place can reach it readily. It is pivoted on a pedestal 336 beneath the body of the machine. Through a link 337, it connects with the slotted operating arm 338 of the control valve 339 of the air cylinder 47. This valve controls the admission of air from supply conduit 340 and its exhaust from either side of the piston of cylinder 47, by way of conduits 341, 342 leading respectively to the opposite ends of cylinder 47 by way of a combination fitting 343. This cylinder, this fitting, and the arrangements by which this is done, form no part of my invention. Suffice it to say that when the valve 338 is turned in one direction, air is admitted to one end of the cylinder, and when in the opposite direction to the opposite end of the cylinder. Admission of air to the rear end of the cylinder, projects rod 36 forwardly and thereby rotates sleeve 37 and disc 34 to withdraw the clamping fingers 28 and release a wheel which has been clamped in position as shown in Fig. 7. When air is admitted to the opposite end of the cylinder, the rod 36 is withdrawn, thereby clamping a freshly placed wheel in place.

These operations are made use of to automatically close the clutches of the several mechanisms of the machine and to set them all in operation. Branches 344, 345 respectively leading from the conduits 341, 342 lead to the lower and upper ends respectively of a clutch-controlling cylinder 346a. Branches 344, 345 are provided with valves 346, 347 by means of which the flow of air

into them is restricted and the operation of cylinder 346a retarded as respects the rapid and vigorous action of the clamping of the cylinder 47 of the clamping mechanism C. Cylinder 346a is located on the left of the machine and secured to its front supporting legs. Within the cylinder is a piston 347 connected with piston rod 348 with the vertically-extending operating bar 349 secured to and guided at the front of the machine by bearing plates 350. This bar is moved up and down by the operation of cylinder 346a coincidently with the clamping and releasing operations of the clamping mechanism C. Its movement is not only retarded by the restrictions in conduits 344, 345, but also by the dash pot 351 surrounding the piston rod 348 between cylinder 346a and the bar 349 and containing oil which flows through the regulatable aperture 352 in its piston 353.

The clutches are operated from the bar 349. The bar carries a laterally-projecting bracket 354 upon which there is pivoted a ratcheting cam lever 355 having a cam face 356 which in its reciprocation engages a cam roller 357 mounted on one side of the operating lever 295. This cam lever 355 is prevented from counter clockwise rotation by its abutment at 358 with the bracket, and is biased to this position by spring 359. It may, however, move freely upwardly against the tension of spring 359. So, when the operating bar 349 is projected upwardly by piston 346, cam 356 engages roller 357 and operates lever 295 to close the clutch of the piercing mechanism "P" and with it throw the clutched-together sections 297-301 of the control shaft, to close not only the clutch 294 of the riveting mechanism R, but also the clutch 305 of the timing mechanism T. Upon downward movement of operating bar 349, cam lever 355 ratchets past roller 357 without effecting any movements of the roller or of the clutches which are controlled through the train or mechanism described. The clutches remain in under the control of the timing mechanism "T". (See Figs. 1, 5, 29 and 30.)

Also operated from the control cylinder 346-A, is that train of mechanism designated by the numerals from 360 to 370. This mechanism is the aligning mechanism for the clutches 293-294-305. It comprises cams 360, 361 and 362, respectively, keyed to the ends of the driving shafts 121, 68 and 189 of the piercing, riveting, and timing mechanisms. These cams are provided each with a radial face, respectively, engaged by followers 363, 364 on the inside of levers 366 and 367, pivotally supported from the frame of the machine, with the exception of cam 362 on shaft 189 in which case the follower roller 365 is secured directly to the link 368 which interconnects the two levers 366 and 367. Lever 366 of this mechanism is provided with a bell crank arm 369 which is connected

by pin and slot 369^a with the ear 370 bolted on to the upright bar 349 of the clutch actuating mechanism. The cam followers engage the cams in a direction counter or opposite to the normal direction of movement of the shafts 121, 68 and 189, and when the control cylinders 347 actuates the bar 349 downwardly, are moved into counter-engagement with the cams 360, 361, 362. The relative dimensions of the parts, and the relative angular positions of the cams on the ends of the three shafts with respect to those positions in which the clutches which they respectively control are truly aligned for immediate closure, are such that when this counter-engagement is effected and the control bar 349 has completed its downward stroke, the clutch jaws are moved into perfect alignment throughout the machine. Coacting with this aligning mechanism, and forming a part thereof is a series of brakes 373 (see Figs. 3 and 4), one operating on each of the three shafts 121, 68 and 189. These brakes (see Fig. 31) comprise drums 374, adjustable brake bands 376 provided with brake lining 375, and an anchorage for the bands 377 by means of which they are pivotally connected with the plane top face of the base "B" (or the bottom face as the case may be) and prevented from riding. By adjusting the brake bands 376 the degree of overthrow of each and all of the shafts 121, 68 and 189, and consequently the degree of overthrow of the clutch members which rotate with them, may be controlled and confined within those reasonable limits in which it is found most effective results are secured from the aligning devices just described. In other words, the widely varying inertias of the several mechanisms and their widely varying friction or other loads are by the brakes prevented from permitting undue overthrow of any mechanism and the several overthrows are brought into substantial uniformity of degree, and reduced to that degree through which the aligning mechanism "A" can most effectively re-align the parts by the counter-engagement set forth. Such is the machine of my invention. Its cyclical operation is substantially as follows.

When compressed air is admitted to cylinder 47 to push its piston forwardly, the clamping mechanism "C" is placed in released position, and a wheel may be freely placed in position against the clamping head 17. When the air is so admitted to cylinder 47, it has also been admitted to control cylinder 346^a. This cylinder has already on its back stroke annulled all overthrow of shafts 121, 68 and 189 incident to the closing of the operations by the timing mechanism "T", and accurately realigned all clutches for instant reentry. A wheel is placed upon the clamping head 17, the foot pedal 335 is pressed, air is admitted to the opposite end of the cylinder 47, the wheel is instantly clamped in place, and immediately

thereafter, because of restrictions in conduits and the dash pot control hereinbefore described, the action of cylinder 346^a throws the control bar 349 upwardly and through the cam lever 355 closes the clutches throughout the machine, for the two sections 297—301 of the control shaft are coupled together in this movement. At this point the shifting mechanism "S" supports the wheel in its raised position. The piercing mechanism "P" is immediately actuated to pierce the first hole. Feeding mechanism "F" at the same time operates in the manner previously described to carry a rivet over to the put-in position 188. But there is no hole there since the first hole pierced is substantially 90° away. So the rivet is not released, but carried back to the pick-up position 160, to be repeatedly presented until the first pierced hole reaches the put-in position 188.

During the piercing operation the wheel was floated upon the piercing thrusts and not subjected to straining or distorting forces of any nature, since the guide rollers 128 of the piercing mechanism, after the cam face 133 engaged the cam follower 122, as shown in Figure 8a, passed to the upper widened portion of the guide way 126, thereby freeing the piercing mechanism from confinement by the walls of the guide-way and effectually floating the entire piercing mechanism bodily upon the wheel. In other words, the entire mechanism in response to differences of dimensions of the wheel, or differences in resistance to piercing, is free to move about the transverse axis of the lower followers 124 in a movement of oscillation. The transverse axis of the followers 124 being located far to one side of the axis of the piercing operation, the floating movement of the piercing dies would be almost if not quite radial whether or not the arms 94—96 bearing these dies were confined to rectilinear movement as shown. By virtue jointly of the incline of the guideways 126 to the right and the closing movement of the toggles of the mechanism, the movement of approach of punch 91 and die 89 is very rapid and it is therefore possible to close them quickly to effect the piercing irrespective of the relatively great height of the rim flanges of the wheel as compared with the thickness of the rim and disc flange to be pierced.

Promptly upon the withdrawal of the piercing mechanism from engagement with the wheel, the shifting mechanism "S" operates to lower the wheel-body about the axis of shaft 12 from the dotted line position shown in Fig. 10 (which dotted line position corresponds to the full line position shown in Fig. 8) to the full line position shown in Fig. 10, in which position the wheel disc flange and the wheel rim lie over against the anvil 231 of the riveting mechanism "R". The riveting mechanism goes through the motions of a

complete riveting operation, but without any effect, first, because there is no rivet now in the riveting position, the first piercing having been accomplished 180° away, and second because there is a slight clearance over and above the thickness of the disc flange and rim between the face of anvil 231 and the punch 232. Upon the close of this riveting operation, the shifting mechanism "S" again shifts the wheel away from the fixed anvil 231 and back to the dotted line position of Fig. 10, or the piercing position of Fig. 8. At the same time the index mechanism "I" indexes the wheel another step. The second and successive piercing, rivet put-in, shifting, riveting, reshifting, and indexing operations follow each other in quick succession as the index mechanism "I" steps the wheel from position to position until the first pierced hole reaches the rivet put-in position 188 approximately vertically below the axis of the clamping mechanism "C" without other effect on the wheel than piercing. For the feeding mechanism "F" is dependent for its effective placement of a rivet, first, upon the presence of a pierced hole in the put-in position, and second upon the empty or full condition of the pierced hole, and the riveting mechanism "R" is in its turn entirely dependent upon the presence or absence of a rivet in the riveting position for its effective operation.

The moment a pierced hole reaches position 188 under the operation of the index mechanism "I", the ensuing put-in movement of the feeding mechanism "F" puts the rivet, which it has until now held in its grasp, into the pierced hole, and withdrawing, leaves it there, for the pierced hole being present in the put-in position, the shank of the rivet is thrust into it and instead of the head of the rivet being thrust against the pin 187 and the wrist 179 (Fig. 20) being moved bodily upwardly while the rivet is still being held by the fingers 178, the ends of the fingers themselves engage the inner face of the disc flange 132 symmetrically and are opened, permitting the head of the rivet to drop upon the face of the flange, and, by reason of its lying there and the engagement of the spherical head of the rivet with the upwardly inclined tips of the fingers, not grasping it again. The fingers therefore now return to the pick-up position 160 empty, and because empty, pick-up a fresh rivet as described. From this time on until the first pierced hole has rotated through 360° there is a rivet put by the feeding mechanism "F" into each pierced hole which comes to rest in the put-in position 188. But after the first pierced hole has rotated 360° and is again located in the put-in position 188, the pierced hole contains a rivet, and the engagement of the shank of any rivet attempted to be put in by the feeding mechanism "F" with the head of the rivet already in, results in the wrist movement of

the part 179 rather than a finger movement of the parts 178, and the rivet carried is retained by the feeding mechanism.

Both the piercing and rivet feeding operations continue in sequence without any effective operation of the riveting mechanism until the first pierced hole, now with other holes occupied by a rivet, reaches the riveting position 230. Thereupon, when the shifting mechanism "S" at the close of the piercing operation corresponding to this position shifts the wheel from the dotted line to the full line position of Fig. 10, the head of the rivet is entered into the cupped seat in the die 264. Immediately thereafter, the punch 232 engages the outer end of the shank and coins the outer end of the shank down into the countersunk rim, firmly riveting rim 131 to disc flange 132. The dimensions of the parts and the lengths of the rivet are such that the riveted ends lie flush with the outer surface of the rim. During this operation, irrespective of the difference of the dimensions of the various portions of the wheel being operated upon and irrespective of differences in initial rivet location and in resistance to riveting, the wheel-body and with it the clamping and indexing mechanism, floats on the riveting thrusts, being freely bodily movably by its gravitational bias against the fixed anvil 233.

In this manner, after the first pierced and rivet filled hole reaches the riveting position 230, the riveting operation becomes effective. The three operations of piercing, feeding in rivets, and riveting, then all take place, once for each step wise movement of the wheel, until the wheel has been rotated through another 180° and the first pierced hole, with a rivet now secured in it, again reaches the piercing position. But at this juncture the piercing mechanism "P" has ceased operating. For the wheel has been indexed 360° and just before this last step of the 360° movement is completed (or from another viewpoint just after the last hole of the 360° series has been pierced) the timing mechanism "T" has by its dog 315 (Figs. 26 and 37) engaged the following end 330 of lever 316 and disengaged the clutch 293 (Fig. 5) which controls this mechanism. This disengagement when the parts of the mechanism "P" are brought to rest by the brake 373, is at such point as to ensure the spacing apart of the punch 91 and the die 89 approximately their maximum extent. Moreover the action of device 324, 326 through storing up energy in spring 325 against the resistance of clutch 293 to disengagement throws the disc 314 and dog 315 past the lever 316 as the resistance of the clutch yields to the built up pressure on spring 325, thereby freeing the lever 316 from dog 315 and conditioning it for a reengagement of the clutch without interference from dog 315 which is now passing.

The cycle of operations continues beyond the 360° movement of the wheel, since the disc 314 of the timing mechanism "T" has so far progressed but 240°, and it must be 5 progressed 360° before dog 317 shall have returned to its initial position as shown in Figure 26 and through engagement with follower 333 of lever 318 disengage the clutches 294 (Fig. 5) and 305 (Fig. 6) controlling 10 the operations of the remaining mechanisms of the machine. So the wheel is indexed step by step by mechanism "I" for yet another 180°. During the first 90° of this movement, approximately, rivets continue 15 to be fed by mechanism "F" to the remaining quarter of the pierced holes. When the last of them has been filled the effective operation of the feeding mechanism ceases. But it continues to attempt to transfer 20 rivets. Each rivet, as heretofore, as it reaches the riveting position 230 is riveted over. As the last one of them is coined into place by mechanism "R", dog 317 reaches its initial position and under an action of 25 the energy storing device 324—325—326 of the timing mechanism "T" (Fig. 26) entirely similar to that in connection with the dog 315 and piercing mechanism "P", disengages simultaneously both clutches 294 and 305, 30 whereupon the entire machine is brought to rest, each of the several remaining mechanisms having been disconnected from the source of power, and brought to rest by the respective brakes 373. This includes the 35 timing mechanism "T" itself, and when so brought to rest dog 317 of the timing mechanism is thrust by device 324—325—326 beyond interference with the following end 333 of lever 318; whereby clutches 294 and 305 40 are, like clutch 293, again free to be closed upon the initiation of the next operating cycle upon which the machine is to be engaged.

Upon pressing foot lever 335 the completed wheel is released by clamping mechanism "C", first the heavy clamping pressure of plate 34 being withdrawn and then as pin 38 (Figs. 7 and 35) passes from the straight inner end to the spiral middle 50 portion of slot 39, the plate 34 is rotated counter-clockwise to withdraw the clamping fingers 28 within the periphery of the boss 26. The wheel may then be freely removed, for mechanisms "R" and "P" have both been 55 stopped with their dies and punches spread apart substantially the maximum extent, they both open on the front of the machine, and the remaining mechanisms are located behind them and behind the body of the 60 wheel. In fact, the clamping mechanism "C" and the riveting mechanisms "R" and "P" are all located in substantially the vertically extended frontal plane, or front face, of the machine whereby not only is the 65 clamping mechanism "C" freely accessible

for the placement and removal of wheels, but that free placement and removal is not interfered with in any way by the bodies of those mechanisms. Nor are there projecting parts of any of these mechanisms which may interfere with the freedom of movement and safety of the operator. 70

A cycle may be repeated as rapidly as a preceding cycle has been completed, all that it is necessary for an operator to do being to 75 press the foot lever 335 once to release the finished wheel and through the mechanism 360 to 370, realign the clutches for the new cycle, and once again to clamp in position the fresh wheel upon which the next cycle 80 is to be carried out.

Obviously so adaptable in mechanism, the apparatus and process are capable of many modifications, without departing from the generic spirit of the invention involved. For 85 example, any equivalents of the several mechanisms and their associated parts known or to be known may be substituted in the general ensemble by such change only as is needed to adapt it to the location in which it is 90 to be put, the space available, and the relative dimensions of the associated parts and the work. Thus for example, a different form of rivet feeding mechanism might be used. So two different forms of adjustability and 95 replacement of parts may be used with a view to continuing in the machine that general adjustability of size and type of which my invention is capable, as has been pointed out. For example, the adjusting 100 wedges 105 and 243 may take any form known or to be known, and suitable clearances are to be provided in the fixed frame to enable the wedges to operate freely. Also the degree of movement required of any or 105 all of the parts may be varied to suit any special conditions. Thus for example, the difference in width of the guide-ways 126 (Fig. 8 and Fig. 8a) between the bottom of the guide-way (or more properly speaking that portion traversed by the follower 122 before the piercing face 133 engages the follower) and the upper portion of the guide-way may be varied. Only a slight 110 difference is shown. For accurately dimensioned wheels, only a small fraction of an inch is necessary, perhaps only a few thousandths or hundredths, to secure the effective floating of the mechanism, but for inaccurately made wheels a much larger 115 amount may be necessary. Until the follower 122 is engaged by the piercing face 133, the guide-way 126 is straight, though substantially inclined to the right as set forth. The degree of inclination itself may 120 be varied.

Finally it should be pointed out specifically that the relative timing of the operations of the several mechanisms may be varied at will. The particular timing and sequential order 130

of the operations may be varied to suit the nature of the work being done and the rate of speed at which it is desired the apparatus shall work. The general contours of the actuating cams of the several mechanisms has been clearly outlined, but no attempt is made to prescribe a specific timed relation between them since each case will require its own treatment. To illustrate, for very rapid 10 production, the following sequence of operations will be found of advantage; the operation of the piercing mechanism "P", the operation of the shifting mechanism "S" to carry the wheel to the riveting position, the 15 operation of riveting, the operation of indexing or stepping the wheel to the next position, and simultaneously with the latter the operation of shifting back to piercing position carried out by the shifting mechanism 20 "S". The rivet may be fed by mechanism "F" either during the interval of the piercing operation or the interval of the riveting operation, but is preferably fed during the interval of piercing when the period is longer. 25 The essential item is that the rivet shall be fed when the wheel is at a standstill.

I am aware that the embodiment of my invention which I have described and illustrated in this specification, may be changed 30 considerably without departing from the spirit of my invention and therefore, I am not to be restricted to the particular embodiment illustrated but claim my invention broadly as indicated by the appended claims. 35

What I claim is—

1. A machine comprising a piercing mechanism, a riveting mechanism, an indexing mechanism driven by said riveting mechanism, a controlling mechanism, a rivet-feeding mechanism and a shifting mechanism 40 driven from a common shaft, separable clutches connecting said piercing mechanism, said riveting mechanism and said shaft to a common source of power, said clutches being under the control of said controlling mechanism.

2. A machine of the character described comprising a rotatable wheel-clamping device, piercing and riveting mechanisms on 50 opposite sides of said clamping mechanism and in the same plane, a rivet feeding mechanism and a wheel-indexing mechanism each arranged behind the plane of said piercing and riveting mechanisms, and means operationally relating said mechanisms.

3. A machine of the character described comprising a rotatable wheel-clamping device, piercing and riveting mechanisms on opposite sides of said clamping mechanism 60 and in the same plane, a rivet feeding mechanism behind one of said piercing and riveting mechanisms, and a wheel-indexing mechanism behind the other of said mechanisms, together with a timing mechanism coordinating the operations of the several other mech-

anisms upon the wheel located intermediate of said piercing and riveting mechanisms.

4. A machine of the character described, a revolvable clamping mechanism, piercing and riveting mechanisms associated therewith, 70 together with means for operating the piercing mechanism for a full revolution of the clamping mechanism and then automatically stopping said piercing mechanism, and for automatically rendering the riveting 75 mechanism operative after a partial revolution of the clamping mechanism.

5. A machine of the character described, a rotary wheel-clamping mechanism, and wheel-piercing and riveting mechanisms associated therewith, together with means for operating the piercing mechanism for a full revolution of the wheel-clamping mechanism and then automatically stopping said piercing mechanism and for operating the riveting 80 mechanism for more than a full revolution of the wheel-clamping mechanism before stopping it.

6. A machine of the character described, a rotary wheel-clamping mechanism, and wheel-piercing and riveting mechanisms connected therewith, together with means for operating the piercing mechanism for a full revolution of the wheel clamping mechanism and making the riveting mechanism operative 90 after a part revolution of the wheel-clamping mechanism, together with a wheel-indexing mechanism operated for the same period as the wheel-riveting mechanism. 95

7. A machine of the character described 10 comprising a rotary wheel-clamping device, a wheel-piercing device operated for a full revolution of a wheel clamped in said device, together with a rivet-feeding mechanism, a riveting mechanism, and a wheel-indexing 10 mechanism all operated for more than the full revolution of said wheel by the angular distance between the point at which the piercing mechanism and the point at which the riveting mechanism engage the wheel, said rivet-feeding and riveting mechanisms becoming operative subsequent to the starting 11 of the piercing operation.

8. A machine of the character described comprising means to clamp a wheel in position to be operated upon, mechanisms which form the wheel body to receive rivets and mechanisms to place and to operate upon the rivets, grouped about said clamping device, means to produce relative angular movement 12 between said clamping device and the several mechanisms grouped thereabout to bring a different circumferential part of the wheel into operative relation to said mechanisms, and timing means controlling the period of 12 operation of the mechanism forming the wheels to receive rivets and those other mechanisms which place and operate upon the rivets.

9. A machine device of the character de- 13

scribed comprising a wheel-clamping device engageable with the wheel at its hub portions, together with a wheel-piercing mechanism, a rivet-feeding mechanism and a riveting mechanism angularly spaced about the clamping device in the order named, means for relatively rotating a wheel clamped on said device and said mechanisms, and means for coordinating the action of said device and said mechanisms to bring about the riveting of the wheel around its entire circumference without stoppage of the machine.

10 10. A machine of the character described comprising a wheel-clamping device, a wheel-piercing device, and a wheel-riveting device, together with means to shift the wheel-clamping device bodily with respect to one of said piercing and riveting devices, and means to allow bodily movement of the other of said 20 piercing and riveting devices with respect to the wheel-clamping device.

11 11. A machine of the character described comprising a wheel-clamping mechanism acting on the wheel from its front, and a power-operated device for said clamping mechanism in the rear thereof, and an index mechanism on the axis of the clamping device, said power-operated device and the clamping mechanism being bodily shiftable together.

12 12. A machine of the character described comprising a mechanism for operating upon the wheel to effect the riveting, means for shifting the wheel and said mechanism relatively to each other to float the wheel on the riveting mechanism, and an index mechanism for the wheel partaking of said shifting movement.

13 13. A machine of the character described comprising a rotating clamping mechanism adapted to securely hold a wheel having a plurality of pierced holes therein, means for positioning a rivet successively in each of said holes as said wheel rotates, and means for preventing dislodgment of said positioned rivets during said rotation.

14 14. A machine of the character described comprising a rotary work-clamping mechanism, means for indexing said work from position to position, and means for placing a plurality of rivets in said work corresponding to the number of indexed positions.

15 15. A machine of the character described comprising a work-clamping mechanism, means for imparting an oscillatory movement to said work-clamping mechanism to move the work bodily from a lowered to a raised position, means for piercing holes in the said work while the latter is in said raised position, additional means for placing rivets in said pierced holes while said work is in said raised position, and means for riveting while the work is in the lowered position.

16 16. A machine of the character described comprising a wheel-shifting means for oscillating a wheel from a lowered to a raised

position, rivet-feeding mechanism for placing a plurality of rivets for said wheel while the latter is in said raised position, and riveting mechanism for riveting said rivets while the wheel is in its lowered position.

70

17. A machine of the character described comprising a wheel-clamping mechanism, and a wheel-riveting mechanism, said clamping mechanism being mounted so as to be freely oscillatable on an axis transverse to the axis of said riveting mechanism, whereby the wheel is floated on the riveting mechanism.

75

18. A machine of the character described comprising a wheel-riveting mechanism and a shifting wheel mechanism, said shifting mechanism being shiftable on an axis transverse to the riveting axis and located in a transverse plane midway between the extremes of relative separation between the punch and die of the riveting mechanism.

80

19. A machine of the character described comprising wheel piercing mechanism, a wheel-riveting mechanism having a fixed anvil thereon, holding means for a wheel having a rivet hole pierced therein, said holding means holding the wheel out of contact with said anvil and with the rivet hole out of alignment with the riveting axis during the piercing operation, and shifting means for shifting said holding means to a position over the anvil such that the pierced hole occupies the riveting position.

85

20. A machine of the character described comprising a wheel-mounting mechanism, a wheel-piercing mechanism, a wheel-riveting mechanism, separate jaw clutch mechanisms for effecting operation of certain of said mechanisms, means for actuating said jaw clutch mechanisms and means to effect a simultaneous relative movement of the elements of said several clutch mechanisms whereby to insure the alignment thereof.

90

21. A machine of the character described comprising a wheel clamping mechanism adapted for rotatable movement, a wheel piercing mechanism, a wheel riveting mechanism and a timing mechanism, the latter of which stops the piercing mechanism in its operation prior to the stopping of the riveting mechanism.

100

22. A machine of the character described comprising a wheel clamping mechanism adapted for rotatable movement, a wheel piercing mechanism, a wheel riveting mechanism and a timing mechanism, the latter of which stops the rotation of the clamping mechanism upon the completion of the riveting operation.

105

23. A machine of the character described, comprising piercing and riveting mechanisms adjacent an oscillatable work-clamp, common means for operating said piercing and riveting mechanisms and for oscillating said work-clamp, said work clamp being op-

110

erated positively in its oscillation toward said piercing mechanism and resiliently toward said riveting mechanism, said piercing mechanism being comprised of piercing elements each movable relative to said work and to each other, said riveting mechanism having one of its elements fixed.

24. In a machine for riveting rims to wheel discs or the like, a work-piece carrier; a piercing device, a rivet-feeding device, a riveting device and a timing device all grouped about said carrier; said carrier being relatively rotatable with respect to said devices; and disconnectible means joining said devices to a common source of power and operated by said timing device to effect successive stoppage of said devices.

25. In a machine of the class described, a piercing device, a riveting device, a shiftable work-piece carrier, means for shifting said work-piece carrier positively to move the work into the riveting position, said means permitting a yielding return of the carrier to riveting position to complete a cycle of the shifting movement, and rivet-feeding mechanism operable at each cycle of shifting movement.

In testimony whereof I hereunto affix my signature.

30

EDWARD BOARD.
